UNITED STATES PATENT OFFICE.

ARTHUR P. SMITH, OF PORTLAND, MAINE, ASSIGNOR OF ONE-HALF TO RALPH W. SMITH, OF ALFRED, MAINE.

EXTENSION-PEDAL.

1,278,773.

Specification of Letters Patent. Patented Sept. 10, 1918.

Application filed February 2, 1918. Serial No. 215,116.

To all whom it may concern:

Be it known that I, ARTHUR P. SMITH, a citizen of the United States, residing at Portland, in the county of Cumberland and 5 State of Maine, have invented new and useful Improvements in Extension-Pedals, of which the following is a specification.

This invention relates to an attachment or extension for the pedals of pianos where- 10 by the same may be conveniently used by small children when playing a piano.

The primary object of the invention is to produce a device of this character which may be readily and securely attached to the 15 piano, wherein the pedals may be adjusted to properly engage with the piano pedals of varying elevations from the bottom of the piano.

It is a further object of the invention to 20 produce an attachment for this purpose which shall be of an extremely simple construction, ornamental in appearance, cheap in manufacture, and which will perform the function for which it is devised with 25 ease and with accuracy.

Other objects and advantages will appear as the nature of the invention is better understood, reference being had to the accompanying drawings, in which,

30 Figure 1 is a perspective view illustrating the application of the improvement.

Fig. 2 is a top plan view of the improvement.

Fig. 3 is an end elevation thereof.

35 Fig. 4 is a sectional view approximately on the line 4—4 of Fig. 2.

Fig. 5 is a sectional view approximately on the line 5—5 of Fig. 2.

While in the drawings I have illustrated 40 the piano 7 as provided with three pedals 8, my improvement may be successfully em- ployed on pianos with only two pedals.

The improvement includes a boxlike cas- 45 ing 9, the inner face of which being open, as is also the bottom thereof. The lower edges of the casing 9 have arranged thereon cushion members 10, providing the feet for the casing, and the inner straight edges of the casing have arranged thereon a facing 50 of compressible material providing cushions 11 which are designed to contact with the lower portion of the piano, when the device is applied, so as not to mar or injure the piano.

55 On the inner sides 12 of the casing 9 are

pivotal secured, as at 13, the inner ends of clamping jaws 14. These jaws project a suitable distance beyond the inner end of the casing 9 and have their upper edges provided with a facing of compressible ma- 60 terial 15. Passing through openings in the top of the casing and through threaded openings in the jaws 14 are screws 16, the upper or outer ends of the said screws being headed as at 17, and by turning the 65 screws the jaws 14 will be brought toward or away from the top of the casing 9. The jaws are designed to be arranged beneath the piano and are brought into contact with the lower edge of the piano by the adjust- 70 ment of the screws 16, whereby to hold the improvement against the piano.

Preferably the top of the casing 9, in- 75 ward of the corners thereof is reduced and provided with three longitudinally disposed, equally spaced slots or openings 18, and in these openings are designed to be arranged the outer angular ends of the pedals of the improvement.

As the pedal members are each of a simi- 80 lar construction, the reference characters referring to the parts of one are to be considered equally applicable to similar parts of the others. The pedals are broadly indicated by the numerals 19 and include each 85 a substantially rectangular body 20 having its inner edge pivoted, as at 21, in the casing 9. Each of the pedals 19, upon its inner end is provided with an eye or hook 22 that is engaged by a helical spring 23, the 90 outer end of each of the springs being connected with a bolt 24 that passes through an opening in a cleat 25 suitably secured in the casing. Screwed on the bolts 24 are nuts 26 which contacting with the under face of the 95 cleat 25 adjust the tension of the springs 23, and consequently the upward swinging move- 100 ment of the pedals influenced by the springs. The top portions of the pedals 19, at the outer ends thereof are provided with angular extensions 27, and one of these exten- 105 sions is received in each of the slots or open- 110 ings 18. The outer ends of the extensions are preferably rounded and have arranged thereon a metallic protector plate 28. The casing 9, upon the top thereof, and at a suit- able distance away from the ends 27 of the pedals 20 is provided with a heel rest 29, the same preferably comprising a strip of rubber, but, as the device, for the sake of

cheapness is mainly constructed of wood, a metallic heel rest instead of an elastic or compressible heel rest may be employed.

The body portion 20 of each of the pedals 19, upon its lower surface, and from its outer end is formed with a longitudinally arranged notched or cut-away portion 30 within which is received an element in the nature of an arm 31. This arm 31 is 10 hingedly connected to the lower edge of the body 20, as at 32, and the outer edge of the arm 31 is rounded transversely, as at 33. To the rounded end of the arm 31 is secured, as at 34 a metal plate 35, the same being provided with a central elongated slot 36 and having its upper end curved outwardly, as at 37. One of the plates 35 is designed to be arranged against the outer edge of the extension 27 of the pedal 19, and passing 15 through the slots 36 of each of the plates 35, and entering the said angular ends 27 of the pedals are the threaded shanks of spaced binding members 38. By adjusting the members 38 it will be noted that the arm 31 20 may be swung and retained at any desired angle with respect to the pedal 19. It will be further noted that the elements 38 are disposed above the top of the casing 9, and as the same are also arranged a suitable 25 distance outward of the piano proper adjustment of the arms 31 may be made after the device has been arranged on the piano it will be obvious that such adjustment may be made before the device is attached to the 30 piano.

From the foregoing description, when taken in connection with the drawings it is believed that the simplicity, the easy manner in which the same may be applied to or 40 detached from the piano, the operation thereof, the cheapness of the construction as well as the advantages of the improvement will be apparent, to those skilled in the art to which such inventions appertain 45 without further detailed description, it being understood that when the device is arranged upon a piano having two pedals, two of the pedals of the improvement are arranged over the piano pedals, and, of 50 course, when the device is arranged upon a piano having three pedals each of the pedals of the improvement is arranged over and in contact with the piano pedals.

It is to be also noted that by arranging

the slotted plates on the rounded outer ends 55 of the arms, the said plates may be arranged at any desired angle with respect to the said arms, so that the plates will properly engage with the outer faces of the pedal extensions, or with the angular ends of the 60 said pedals, regardless of the angle to which the same is swung with respect to the pedal.

What I claim is:

1. In a device of the class described, a boxlike casing having an open end, pivoted 65 jaws in the casing extending through the said open end, means exterior of the casing for adjusting said jaws with respect to the top of the casing, a series of pedals pivoted in the casing, eyes on the inner ends of said 70 pedals, springs connected to said eyes, bolt members on said springs, a cleat in the casing having openings through which the bolts pass, and adjusting nuts for the bolts contacting with the under face of the cleat. 75

2. In a device of the class described, a boxlike casing, jaws extending therethrough, adjusting means for said jaws, spring influenced 80 pedals pivoted in said casing, said pedals having outer angular ends passing 85 through slots in the top of the casing, an arm hingedly connected with the under face of each of said pedals, a slotted plate loosely connected with the arm, said plates arranged over the outer faces of the extensions of each of the pedals, and binding elements passing through the slots of said 90 plates and contacting with the plates and entering the extensions of the pedals.

3. In a device of the class described, a 90 boxlike casing, clamping means therefor, a series of pivoted spring influenced pedals in the casing, each of said pedals having an angular end projecting through openings 95 in the top of the casing, each of said pedals having its lower edge notched longitudinally, an arm in said notch having its outer end rounded, said arm having its inner end hingedly connected to said pedal, a slotted 100 plate loosely connected to the rounded end of the arm and arranged over the outer face of the pedal extension, and binding elements contacting the outer face of the plate and passing through the slot thereof and entering the angular end of the pedal. 105

In testimony whereof I affix my signature.

ARTHUR P. SMITH.
